DESIGN FOR A DRESS

Gisele Klein, New York, N. Y.

Application December 8, 1938, Serial No. 81,650

Term of patent 3½ years

To all whom it may concern:

Be it known that I, Gisele Klein, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein

The characteristic feature of my design resides in the particular stitchings on the waist section of the dress as shown.

I claim:

The ornamental design for a dress, substantially as shown and described.

GISELE KLEIN.
